UNITED STATES PATENT OFFICE.

WILLIAM C. BRYCE, OF MONTREAL, QUEBEC, CANADA.

AUTOMATIC VALVE FOR DRY-PIPE FIRE-SPRINKLER SYSTEMS.

1,091,803.

Specification of Letters Patent. Patented Mar. 31, 1914.

Application filed June 21, 1913. Serial No. 775,125.

To all whom it may concern:

Be it known that I, WILLIAM C. BRYCE, a subject of the King of Great Britain, residing at 250 Peel street, Montreal, Province of Quebec, Canada, have invented certain new and useful Improvements in Automatic Valves for Dry-Pipe Fire-Sprinkler Systems; and I do hereby declare that the following is a full, clear, and exact description 5 of the invention, such as will enable others skilled in the art to which it appertains to make and use the same.

The invention to be hereinafter described relates to automatic valves for dry pipe fire 10 sprinkler systems.

In order to more clearly disclose the construction, operation, and use of the invention, reference should be had to the accompanying drawings forming part of the 15 present application.

The main objects of the invention are, to produce a single-chamber, straight-way valve, for sprinkler systems, which will offer a minimum of resistance to the flow of the 20 water when in use, which will effectively prevent water columning, will not employ any springs or similar easily broken parts in its construction, and which will contain all of the operative and adjusting means of the 25 valve within the valve casing so as to effectually prevent the valves being tampered with.

The single figure of the drawings is a central, vertical, longitudinal, cross section 30 through the invention, with valves seated.

Referring to the drawings in detail, 1 indicates the upper, and 2 the lower casting or 35 section of the valve casing, each provided with an attaching flange complementary to 40 the flange of the other and adapted to be securely clamped together by bolts and nuts in the usual manner. The lower casing section is provided with an inlet passage 3 leading 45 from the water main and has a by-pass 4 leading laterally from this passage toward one side of the casing, for a purpose to be 50 later described. Within the section 2 are mounted all operative parts, thus insuring alinement of the parts and, also, insuring 55 no outside levers, &c., to be tampered with.

The upper section 1 is provided with a hand hole 5 closed by a removable cover plate 6 bolted in place in the usual manner. Also, this upper section is connected direct to the 55 riser by passage 7, in the usual manner. The result is that it is absolutely necessary to

securely bolt the cover 6 in correct operative position before pumping in the air pressure, otherwise, the air will escape as fast as it is pumped in. Thus, no water damage can result from defective fastening or misplacement of the cover plate.

The inlet passage 3 is provided with the usual valve seat which receives a valve 8 of well known construction which is pivoted to 60 a lever 9 fulcrumed at 10 in the lower casing section 2. The opposite free end of the lever is provided with a bore to receive the threaded end of a trigger bolt 11 which may be adjusted toward and from the lever end 65 and secured in such adjusted positions by means of set nuts 12 threaded thereon, as will be clear. The tip or point 13 of this trigger bolt engages a toe 14 extending from one branch of a bell crank lever 15 fulcrumed at 70 16 in the lower casing section 2. To the free end of the other branch of the bell crank lever is pivotally connected a differential 75 valve 17 which closes that end of by-pass 4 which opens into the lower casing section 2. 80 This valve 17 is made with a differential ratio of 1 to 6, i. e. with such relative upper and lower operative surfaces that an air pressure of 10 pounds in the valve casing will counterbalance a water pressure of 60 85 pounds in the by-pass 4 and passage 3. Thus, at slightly over 10 pounds pressure in the casing, the valve 17 will be kept closed against a 60 pound water pressure in the by-pass 4 and inlet passage 3. On the other 90 hand, the opposite operative surfaces of valve 8 being practically the same in area, it is necessary to have the trigger bolt 11 engaged beneath the toe 14 to prevent the valve 8 from flying open. The force exerted 95 by bolt 11 on toe 14 is at right angles to the axis of rotation of the bell crank lever 15. In order to overcome any friction between 13 and 14 and to insure more positive action of valves the toe 13 is placed slightly off 100 center of pivotal point 16 resulting in slight lifting force on bell crank lever 15. Now, as soon as the air pressure in the casing drops below the predetermined point, the water pressure in the by-pass will swing the 105 valve 17 from its seat, thereby rocking the bell crank 15 and disengaging toe 14 from the tip 13 of the trigger bolt 11. At this point, the pressure on the under face of the valve 8 will drive it open and the water will 110 rush into the riser and branches in the usual manner. Due to the substantial equality of

operative surfaces of valve 8, there will be no probable tendency to water columning. However, should there be any such tendency, it will first affect the differential valve 17 and drive it shut, due to the greater operative area of its upper face. The toe 14 will then be in the direct path of the trigger bolt 11 and will be engaged thereby, should the valve 8 drop toward its seat. This engagement will, obviously, prevent seating of valve 8, thereby absolutely preventing any possibility of water columning. As the tip 13 wears, or to keep a tight joint between the valve 8 and its seat, adjustment of bolt 11 will be amply sufficient.

It is thought that the construction, operation, and use of the invention will be clear from the preceding detailed description.

Changes may be made in the construction, arrangement, and disposition of the several parts of the invention without in any way departing from the field and scope of the same, and it is meant to include all such within this application wherein only a preferred form has been disclosed.

Having thus fully described my invention, what I claim as new and desire to secure by Letters Patent is:

1. In a single-chamber, straight-way valve 30 of the character described, a valve casing section provided with an inlet passage and a by-pass, a lever pivotally mounted in said section, a valve carried thereby, and adapted to close said passage, a trigger bolt carried 35 by said lever, a bell crank lever mounted in said section and adapted to engage said trigger bolt, and a differential valve carried by said bell crank lever and adapted to close said by-pass.

2. In a single-chamber, straight-way valve 40 of the character described, a valve casing section provided with an inlet passage and by-pass, a lever pivotally mounted in said section, a valve carried thereby and adapted to close said passage, a trigger bolt mounted 45 in the free end of said lever and provided with an off set tip, a bell crank lever fulcrumed in said section and provided with a toe adapted to engage said tip, and a differential valve carried by said bell crank and 50 adapted to close said by-pass.

3. In a single-chamber, straight-way valve; a single valve chamber provided with aligned inlet and outlet passages; a by pass leading from the inlet passage and communicating with the valve chamber, at a point a little below the delivery end of the inlet passage; a lever pivotally mounted in said valve chamber; a valve carried thereby, and adapted to close the delivery opening of 60 said inlet; a second lever mounted in said casing; a differential valve carried thereby and adapted to close said by pass; connections between said levers; a trigger bolt carried by the first lever and engaged by 65 the second lever; and means for adjusting said trigger bolt; the said valves, their connecting and co-operating parts, and adjusting means, being contained wholly within the valve casing, to prevent their being tampered with.

In witness whereof I have hereunto set my hand in the presence of two witnesses.

WILLIAM C. BRYCE.
